UNITED STATES PATENT OFFICE.

JOSEF KRYSZTOFIAK, OF NEW YORK, N. Y., ASSIGNOR TO L'AUREOLE CO., INC., OF NEW YORK, N. Y., A CORPORATION OF NEW YORK.

HAIR-CURLING DEVICE.

Application filed October 4, 1923. Serial No. 666,636.

To all whom it may concern:

Be it known that I, JOSEF KRYSZTOFIAK, a citizen of the Republic of Poland, and residing at 4174 Park Avenue, New York city, have invented certain new and useful Improvements in Hair-Curling Devices, of which the following is a specification.

My invention relates to hair curling devices for producing permanent waves in hair, and more particularly to the type of devices disclosed in my United States Letters Patent, No. 1,474,334, November 13, 1923, on which this application is an improvement.

15 The object of this invention is to provide a pencil for use in hair curling devices, so constructed as to enable the operator to securely wrap the strand of hair closely around the pencil preparatory to treatment, 20 and to retain the hair in its proper position on the pencil and under the desired strain, during the operation of curling it.

I have found it to be of vital importance, in practice, to wrap the hair tightly upon 25 the pencil and to hold it firmly in place, in order to secure the proper wave, for the reason that a permanent wave is accomplished by rearranging the cells of the cortex and cuticle of the hair, and causing 30 the cells to remain in their new positions. It is necessary, therefore, to provide means whereby the hair is securely held in position on the pencil during the operation of curling.

35 Referring to the drawing:

Fig. 1 is an assembled view of my complete hair curling device.

Fig. 2 is a view of the pencil around which the hair is wound and secured.

40 Fig. 3 is a view partly in section, of the pencil.

Fig. 4 is a sectional view of Fig. 3 at 4-4, looking from the left.

45 Fig. 5 is an end view of the tubular ratchet at 18.

This invention applies more especially to the pencils used in hair curling devices.

Fig. 1 shows one form of curling device, with the pencil located therein, in dotted 50 lines.

I wish to make it clear that my pencil is not restricted in its use to any particular form of heater, as it is my intention to furnish these pencils for use generally with 55 all forms of heaters in practice.

My pencil comprises a sleeve, 11, on which the strand of hair is wound, a head, 8, and a terminal, 12, rotated by the head. A ratchet device is located between the head, 8, on the one hand and the terminal, 12, and the 60 sleeve, 11, on the other, as hereinafter described. The sleeve, 11, is tubular in form, having a smaller diameter at the terminal end and a gradually increasing diameter towards the center of the sleeve. The balance 65 of the length of the sleeve may be slightly tapered. The thickness of the walls of the sleeve, 11, may be uniform or substantially so. Rotatably assembled at one end of the sleeve, 11, is a terminal, 12, provided with 70 a shoulder, 21, and a portion, 20, of less diameter than the terminal, 12, and having a free fit in the smaller end of the sleeve, 11. The end of the terminal, 12, is slotted 75 at 13, or otherwise provided with means for securing the scalp end of the strand of hair to the same. In the present instance, the slot, 13, provides means for securing the hair to the pencil by means of a string or tape. It would not depart from the spirit 80 of my invention to provide a clamp or spring at the end of the sleeve for this purpose.

Secured to, or integral with, the terminal, 12, is a concentrically disposed rod, 25, which runs through the longitudinal axis of the pencil to the opposite end of the same. The end of the rod, 25, is threaded to receive the nut, 9, which latter bears against one end of a spiral spring, 32, the opposite end of 90 which bears against a shoulder, 33, in the hole, 26, passing through the head, 8. The end of the head, 8, opposite to the nut, 9, is provided with an enlarged diameter forming a shoulder, 15, against which the end 95 of the tubular ratchet, 17, seats and also a second enlarged diameter forming a recess, 16, to receive the larger end of the sleeve, 11. The ratchet, 17, is forced into or otherwise secured to the head, 8, so that it rotates with 100 it. The end of the ratchet, 17, which seats against the shoulder, 15, is partly enclosed, forming a keyhole opening as shown in Fig. 4, permitting the rod end, 30, and the flattened portion, 31, of the same to pass through the 105 hole, but not permitting the flattened portion to rotate in the hole. The shaft, 30, therefore, rotates with the head, 8. The outer end of the ratchet is provided with 110 teeth, 22, of about the shape shown in the 115

drawing. A second ratchet having similar teeth to the ratchet, 17, is secured to the inside of the sleeve, 11, with the teeth of the two ratchets, 17 and 19, facing each other. Between the ratchets 17 and 19, I provide a third ratchet, 18, free to rotate on the shaft, 30, and in the sleeve, 11, and having similar teeth at each end to the teeth of the ratchets 17 and 19. All of the teeth of the ratchets 17, 18 and 19, normally engage each other, as shown in Fig. 3.

This construction permits the head, 8, and terminal, 12, to be rotated in either direction with reference to the sleeve, 11, with a smooth ratchet motion, and retain its adjusted position with as much force as desired. The resistance to the device rotating out of adjustment is determined by the spring, 32, which can be adjusted by the nut, 9, to give a greater or less pressure upon the teeth of the ratchets 17, 18 and 19. As the ratchet teeth pass over each other, the head, 8, moves longitudinally against the spring, 32, which latter at all times tends to bring and hold the ratchet members in the positions shown in Fig. 3.

The operation of my pencil will now be easily understood. The strand of hair to be curled is secured near the scalp end to the terminal, 12, by securing it with a string or otherwise, and is then wrapped upon the sleeve, 11. The opposite end of the hair is then secured to the sleeve, 11, by tying or otherwise. The terminal is now rotated by means of the head, 8, with reference to the sleeve on which the hair is wound, until the strand of hair is tightly wound on the sleeve. The hair is usually subjected to a treatment of alkalis and oils, after it is coiled upon the pencil, and is wrapped with felt or flannel or the like,—one method being disclosed in my United States Patent No. 1,440,163, issued December 26, 1922. The pencil and hair and wrappings are inserted in the electric heater, 2, as shown in dotted lines in Fig. 1, and the hair is heated for a given time to the degree desired. A fingered spring clip, 7, holds the pencil in place in the heater. The current is carried to the heater, 2, by leads, 9, secured to the handle, 4, by a strap, 5, insulated from the leads, 9, by insulating tube, 29, and clamped in position by bolt and nut, 27. The heater, 2, is provided with an insulating collar, 3, for handling it. A clamp, 28, is provided at one end of the heater for the hair near the scalp, and is operated by the heat insulating collar, 6, similarly to the method disclosed in my United States Letters Patent No. 1,474,334, November 13, 1923.

What I claim and wish to secure by Letters Patent is:

1. A pencil for a hair curling device, comprising a sleeve upon which the hair may be wound, a shaft passing through the sleeve, 65 three ratchet members interposed between the sleeve and the shaft, one ratchet member adapted to be driven by the sleeve, another ratchet member adapted to be driven by the shaft, both of said ratchet members having 70 teeth facing in the same direction, a third ratchet member normally engaging therewith, and resilient means adapted to hold all of the ratchet members in engagement with each other. 75

2. A pencil for a hair curling device, consisting of a sleeve upon which the hair may be wound, a shaft in the sleeve, a ratchet member driven by the sleeve, a ratchet member driven by the shaft, and means between 80 and normally engaged with both of the ratchet members, adapted to receive motion in one direction only, alternately from one ratchet or the other. 85

3. A pencil for a hair curling device, comprising a sleeve, a shaft in the sleeve, a ratchet rotated by the sleeve, another ratchet rotated in one direction only by the first named ratchet, and a third ratchet adapted to rotate the last named ratchet, also in the 90 same direction, without rotating the sleeve. 95

4. A pencil for a hair curling device, comprising a sleeve, a ratchet adapted to be driven thereby, a head, a second ratchet adapted to be driven by the head, and means 100 interposed between said ratchets, adapted to prevent the movement of the head from effecting a movement of the sleeve. 105

5. A pencil for a hair curling device, comprising a sleeve, a ratchet adapted to be rotated thereby in both directions, a head, a second ratchet adapted to be rotated thereby in both directions, a locking device, 110 engaged with both ratchets, free to move in one direction only. 115

6. A pencil for a hair curling device, comprising a sleeve, a ratchet rotated thereby, a shaft in the sleeve, a second ratchet adapted to be rotated thereby, and means interposed between the ratchets, adapted to be rotated in the same direction, by either ratchet, to prevent the movement of the head from effecting a movement of the sleeve. 120

In testimony whereof, I affix my signature, in the presence of two witnesses.

JOSEF KRYSZTOFIAK.
